UNITED STATES PATENT OFFICE.

FRANK WALKER SMITH, OF REDDITCH, ENGLAND, ASSIGNOR OF ONE-HALF TO THE ENFIELD CYCLE COMPANY, LIMITED, OF REDDITCH, ENGLAND.

OIL-PUMP FOR INTERNAL-COMBUSTION ENGINES.

1,394,042.

Specification of Letters Patent.

Patented Oct. 18, 1921.

Application filed June 5, 1920. Serial No. 386,792.

To all whom it may concern:

Be it known that I, FRANK WALKER SMITH, a subject of the Kingdom of Great Britain, residing at Enfield Works, Redditch, in the county of Worcester, England, have invented certain Improvements in or Relating to Oil-Pumps for Internal-Combustion Engines, of which the following is a specification.

- 10 This invention comprises certain improvements in or relating to oil pumps for internal-combustion engines. According to the present invention the pump cylinder is adapted to oscillate about an axis located 15 transversely to the axis of the said cylinder, and as a result of such oscillation the cylinder port is placed alternately in communication with the ingress and egress ports for the oil. In order to prevent leakage of 20 these ingress and egress ports the pump cylinder is retained in relation to the said ports by a spring.

In order that this invention may be clearly understood and readily carried into practice, reference may be had to the appended explanatory drawings, upon which:—

Figure 1 is a part sectional elevation illustrating an embodiment of the present invention.

- 30 Fig. 2 is a plan of the parts shown in Fig. 1 with certain elements removed.

In a convenient embodiment of the present invention, the pump cylinder takes the form of a drum-shaped body *a* having a 35 cylindrical periphery adapted to enable the said drum-shaped member to oscillate within a correspondingly shaped recess or bearing in the frame of the engine. A diametric cylindrical opening *b* is drilled in the said 40 drum-shaped member, said cylindrical opening being adapted to function as the pump cylinder. In this cylinder a plunger *c* is adapted to work, the said plunger being operated by a crank pin *d* driven in any 45 appropriate manner by or from the timing gear of the engine. This crank pin is adapted to not only reciprocate the plunger *c* within the pump cylinder, but also to oscillate the drum-shaped member *a* in which 50 the cylindrical pump chamber is drilled. At right angles to the pump chamber and at the end thereof remote from the crank pin a lateral port *e* is provided, and as a result of the oscillation of the drum-shaped mem-

ber this port is placed alternately into register with ingress and egress conduits *f*, *g* drilled in the frame or part in relation to which the drum-shaped member oscillates. These ingress and egress conduits are appropriately placed in communication with the supply and delivery conduits *h*, *i* for the oil.

The drum-shaped member has a flat face adapted to bear upon a corresponding flat bearing face provided in that part of the engine frame in relation to which the said drum-shaped member operates, and the said drum-shaped member is retained in oil-tight relationship with this stationary face (in which latter the stationary ingress and egress ports *f*, *g* are provided) by a spring *j* advantageously located on the side of the drum-shaped member remote from that on which the said bearing face occurs. This spring *j* may, for instance, operate between the said drum-shaped member *a* and a closure plate or member *k* which incloses a chamber *l* in which the drum-shaped member, the pump plunger, and the crank pin operate. The spring may be a leaf spring 80 having a central part resting upon the drum-shaped member, and two converging arms extending to the closure member, these converging arms being curved at their extremities in directions away from each other. At 85 a mid-point in the spring the latter may be formed with an indentation adapted to engage with a depression in the drum-shaped member to thereby locate the spring during the operation of the pump. The drum-shaped member *a* may be formed with a depression which accommodates the mid-part of the spring.

The chamber *l* in which the oscillatory parts of the pump operate may assume the 95 form of two substantially circular recesses, in one of which the drum-shaped member oscillates, and the other of which accommodates the crank pin *d*, these two recesses being connected by a narrower channel portion which accommodates the pump plunger.

What I claim as my invention and desire to secure by Letters Patent is:—

An engine frame having a recess including a bearing seat the bottom of which presents a flat surface and is provided with inlet and outlet ports, a drum mounted for oscillation in said seat and on said flat sur-

face and having a bore and a port leading from said bore and arranged to register successively with said port of the frame, a rotary shaft having a crank pin projecting 5 into said recess, a plunger operated by said crank pin and arranged to reciprocate in said bore, a cover for said recess, and a

spring bearing between said cover and the top of said drum and serving to press the latter firmly against said flat surface. 10

In witness whereof I have hereunto set my hand.

FRANK WALKER SMITH.
